VELOCIPED

Arnold Kirchner, Milwaukee, Wis.

Application July 7, 1948, Serial No. 147,415

Term of patent 14 years

(Cl. D34—15)

To all whom it may concern:

Be it known that I, Arnold Kirchner, a citizen of the United States of America, residing at Milwaukee, in the county of Milwaukee and State of Wisconsin, have invented a new, original, and ornamental Design for a Velocipede, of which the following is a specification, reference being had to the accompanying drawing, forming a part thereof wherein:

Fig. 1 is a side elevational view of the velocipede, showing my new design;

Fig. 2 is an elevational view showing the opposite side of the toy shown in Fig. 1;

Fig. 3 is a top plan view thereof;

Figure 4 is a front elevational view thereof; and

Fig. 5 is a rear elevational view thereof.

I claim:

The ornamental design for a velocipede, as shown.

ARNOLD KIRCHNER.
